UNITED STATES PATENT OFFICE.

MILES W. HUFFAKER, OF KNOXVILLE, TENNESSEE, ASSIGNOR OF ONE-HALF TO C. H. FLOURNOY, OF SAME PLACE.

FENCE-POST.

SPECIFICATION forming part of Letters Patent No. 328,946, dated October 27, 1885.

Application filed May 16, 1885. Serial No. 165,746. (No model.)

To all whom it may concern:

Be it known that I, MILES W. HUFFAKER, a citizen of the United States, residing at Knoxville, in the county of Knox and State of Tennessee, have invented a new and useful Improvement in Fence-Posts, of which the following is a specification, reference being had to the accompanying drawings.

This invention relates to fence-posts; and it has for its object to construct a device of this character wedge-shaped in form, so as to be driven in the ground with a hammer or sledge, and thus avoid the necessity of boring a hole to receive the post, as formerly.

15 A further object of the invention is to provide a fence-post which will be held firmly in position while in use, which cannot turn in its seat, and which will be securely braced and steadied in place while attaching the fence-wire or boards thereto.

With these ends in view the said invention consists in certain details of construction and combination of parts, as will be hereinafter set forth, and particularly pointed out in the 25 claims.

In the accompanying drawings, Figure 1 is a front elevation showing my improved fence-post fitted in the ground, with fence-wires attached in position, and also showing the manner of securing boards or plank to the posts when a board or rail fence is being constructed. Fig. 2 is a detail perspective view of a fence-post, the wires or rails being detached therefrom. Fig. 3 is a detail view of a clamp-bolt 30 used in attaching the rails to the face of the post. Fig. 4 is a sectional view through one of the seats for the wires, showing the wedge fitted therein to hold the wire tight. Fig. 5 is a side elevation of the lower portion of the 35 post.

40 Like letters are used to indicate corresponding parts in the several figures.

Referring to the drawings, A designates a flat bar of wrought-iron of any suitable length, 45 width, and thickness, having its lower end, beginning at the point designated by the letter a, tapered or beveled inwardly on its front and rear faces, forming a flat point, b.

C designates foot-braces attached to each 50 side of the bar A at the lower end thereof. These braces consist of two arms, d d', the up-

per arm, d, being welded to the side of the bar or post A adjacent to the point a, and extending outward at an angle thereto, and an arm, d', extending from the other end of the arm d inwardly on an inclined line, so as to come in contact with the post or bar A at the lower extremity thereof, where it is welded in the usual manner. The inner or lower ends, e, of the arms d' have one face made flat to fit the side face of 60 the post or bar, so that in welding the parts together a firm connection is effected, and their front and rear faces tapered or beveled off to correspond with the tapered lower end of the bar or post A.

65 It will be observed that since the braces C are arranged on a line with each other on opposite sides of the bar or post A, and have their lower beveled ends, e, coinciding with the pointed lower end of said post, the latter, in 70 connection with the braces, forms a wedge-shaped point by which the parts may be driven into the ground without the necessity of digging or boring a hole, as formerly. In this manner the fitting of the post in position 75 is expedited and performed with greater ease and facility. The upper arm, d, has its front and rear faces beveled downwardly, as shown, to a cutting-edge, f, and the arm d' is correspondingly beveled outwardly to form a cutting-edge, g, these cutting-edges f g penetrating 80 the ground and thus facilitating the insertion of the posts. The point of junction between the arms d d' is rounded, as at i, and forms the greatest width of the braces, and 85 consequently receives the strain which comes upon the post.

D designates a series of transverse rectangular slots provided along the front face of the post or bar A, and forming seats for the 90 wires of the fence. Slots k are formed through the front face of the post, so as to communicate with the slots D near the center thereof, and thus allow the introduction of the fence-wires through the small slots k into the large 95 transverse slots D. When in position, the wires E rest on the bottom wall of the slots D, and a wedge-shaped block, F, is inserted through the slots above the wires after they are stretched, so as to clamp the latter in their 100 seats and hold them from working loose. Any number of these slots or seats D may be pro-

vided along the face of the bar or post A to accommodate any desired number of lengths or strands of fence-wire. In Fig. 1 I have shown a section of a fence consisting of three strands of wire arranged along the length of the posts, and a railing or plank, G, fitted to the top thereof. A clamp-bolt, H, (seen in Fig. 3,) is passed transversely across one side face of the post A, and has its rear end bent 10 around the same, as at l, and then inwardly, as at m, forming a rectangular portion to clasp the rear end of the post. The front end of the clamp-bolt is threaded, as at n, and is passed through a hole of the plank G, the 15 threaded end extending out therefrom and receiving a nut, p, which binds against the plank and holds it firmly against the front face of the post. In this manner the wooden planks or rails may be secured to the iron 20 posts without the necessity of drilling holes through the latter, and at the same time the planks or rails are detachably and readily fitted in place, so that when they become worthless they may be replaced by new ones 25 in a very short time.

I designate an iron brace having its upper end inserted through or otherwise secured in the post A, and inclined downwardly, and having its lower end turned at an angle, as at 30 q, this flattened end penetrating the ground, so as to secure the brace therein.

It will be apparent that by my construction of posts I am enabled to fit either wires or rails thereto. In this manner the owner may 35 erect either a wire or a rail fence, or he may construct one combining both of these materials.

It will be observed that by constructing the foot-braces C flat on the front and rear faces, 40 and with their greatest width at the right angular turn or point of junction of the arms d

d', said braces will serve to steady the post and prevent the latter from turning while stretching the wires, and will also hold the post from turning while in use. The braces 45 I, which may be arranged on either one or both sides of the post, hold it from moving either way. By my improvements I provide a post which will be strong and durable in use, is readily inserted in the ground, and will 50 always remain in a vertical position.

Having described my invention, I claim—

1. The bar or post A, having the braces secured thereto, said braces comprising the outwardly-extended arm d, having the horizontal inner cutting-edge, f, and the inwardly-extending arm d', having the inclined outer cutting-edge g, as set forth.

2. The bar or post A, having its lower end secured to the sides thereof and having their lower ends pointed and arranged on a line with the pointed lower end of the post, said braces comprising the upper arm, d, and the lower arm, d', the arm d having the cutting-edge f, and the arm d' having the cutting-edge g, for the purpose set forth.

3. The bar or post A, in combination with the braces secured thereto, and comprising the upper outwardly-inclined arm and the 70 downwardly-inclined arm, said arms being set at an angle to each other and sharpened to form cutting-edges, the lower end of the braces being beveled, for the purpose set forth.

In testimony that I claim the foregoing as 75 my own I have hereto affixed my signature in presence of two witnesses.

MILES W. HUFFAKER.
